DRILL GUIDE FOR DOOR LOCK RECESSES

Filed Jan. 12, 1951

Attorney

UNITED STATES PATENT OFFICE

2,609,021

DRILL GUIDE FOR DOOR LOCK RECESSES

Henry L. Griffith, Eclectic, Ala.

Application January 12, 1951, Serial No. 205,757

6 Claims. (Cl. 145—129)

1

This invention relates to a novel construction of drill guide especially adapted for attachment to a door for centering the door relatively to the guide so that a drill bit engaging the guide will be correctly centered relatively to the opposite sides of the door for drilling or boring a recess to receive a lock and to insure that the bored recess will be equally spaced from the two sides or the faces of the door and at a right angle to the door edge out of which the recess opens so that a lock fitted therein will operate correctly.

Another object of the invention is to provide a drill guide having adjustable stop means for limiting the depth of the drilled recess and by means of which recesses of any desired depth may be accurately drilled.

A further object of the invention is to provide a guide which may be readily clamped to or disengaged from doors of different thicknesses and provided with means for positively positioning the guide portion thereof centered with respect to the opposite sides or the faces of the door and perpendicular to the edge of the door in which the recess is to be formed.

A further object of the invention is to provide a guide having reducer means for adapting the guide to doors of different standard thicknesses.

Another object of the invention is to provide a guide of the aforescribed character of extremely simple construction capable of being economically manufactured and sold, which will be durable for accomplishing its intended purpose, and which will save considerable time in accomplishing lock installations in doors and insure an accurate installation.

Various other objects and advantages of the invention will hereinafter become more fully apparent from the following description of the drawing, illustrating a presently preferred embodiment thereof, and wherein:

Figure 1 is a perspective view of the invention;

Figure 2 is a side elevational view, partly in section thereof showing the invention in an applied position;

Figure 3 is a top plan view thereof taken substantially along a plane as indicated by the line 3—3 of Figure 2;

Figure 4 is a vertical sectional view taken substantially along a plane as indicated by the line 4—4 of Figure 2;

Figure 5 is a perspective view of one of a pair of space reducers for use with the drill guide, and

Figure 6 is a cross sectional view taken through the outer end of the fork showing a pair of space reducers applied thereto for fitting the drill guide to a door of a reduced thickness.

2

Referring more specifically to the drawing, a novel drill guide in its entirety which comprises the invention is designated generally 8 and includes an elongated block 9 having a groove 10 of V-shaped cross section formed in its upper surface 11 and which extends from end-to-end of the block 9 and which is equally spaced from the opposite sides 12 of said block. The inner end wall 13 of the block 9 is provided with integral extension bars or furcations 14 forming straight extensions of the side portions of the block 9 which have outer surfaces forming uninterrupted continuations of the sides 12 and inner spaced normally parallel adjacent faces 15 which are spaced apart a distance equal to the thickness of a door of maximum conventional thickness. The block 9 combines with the extension bars 14 to form a fork and the guide groove 10, which opens at its ends into the inner end 13 and outer end 16 of the block 9 is centered with respect to the extension bars 14, the inner faces 15 of which are spaced laterally equal distances from the adjacent edges of the groove 10.

A bar 17 is formed integral with or suitably secured to the bottom surface 18 of the block 9 and has an inner straight edge 19 which is disposed flush with the inner end 13. The bar 17 is centered with respect to the block 9 and to the bar extensions 14. The upper portion of the squaring bar 17 may be widened, as seen in Figures 1 and 2 and is provided with an opening 20 which extends transversely therethrough for slidably receiving the straight intermediate portion 21 of a substantially U-shaped yoke 22. The yoke 22 is provided with substantially parallel end portions or legs 23 and 24 which are disposed in the same plane. The leg 23 is provided with an inturned terminal portion 25 having an enlargement forming a head 26, the inner surface of which faces toward a terminal 27 of the leg 24. Said terminal 27 is inwardly offset relatively to the axis of the leg 24 and is flat, as best seen in Figure 1, and provided with a threaded opening 28. A screw 29 extends threaded through the opening 28 and has a head 30 swivelly mounted on its inner end which faces the head 26. A rod 31 extends through the screw 29 adjacent its outer end and is disposed transversely thereof to form a turning handle for advancing or retracting the clamp head 30.

The block 9 is provided adjacent one of its sides 12 with a longitudinally extending recess 32 in the form of a bore which opens outwardly of the end 16 and terminates adjacent to but spaced from the end 13 to receive a rod 33 which is slidably mounted therein and which projects from

its open end beyond the end wall 16. The rod 33 is provided with an angularly disposed end 34 which projects from the portion thereof which extends from the end wall 16 to provide an adjustable stop, as will hereinafter become apparent. The block 9 is provided with a transverse threaded opening 35 the inner end of which opens transversely into the bore 32, near its open end, and the outer end of which opens outwardly of the adjacent side 12. A setscrew 36 having a turning handle 37 at its outer end is threaded into the bore 35 and is adapted to be advanced into clamping engagement with the rod 33 to hold the rod against sliding and turning movement in the bore 32 when the setscrew 36 is in an advanced position.

The top and bottom edges of the extension bars 14 are provided with longitudinally extending grooves 38 which extend from end-to-end thereof and which open outwardly of the outer ends of said bars. The grooves 38 are disposed adjacent and parallel to the inner extension bar faces 15. A plurality of sets of space reducers are provided each of which includes a pair of spacer bars 39 of a length substantially equal to each extension bar 14. Each spacer bar 39 is provided adjacent each end thereof and at its top and bottom edges with a pair of hook members 40, each of which projects from the same side of the bar 39 and has a right angularly disposed terminal portion 41 extending toward the hook 40 disposed thereabove or therebeneath and which is disposed parallel to the bar 39. A pair of the bars 39 of the same thickness are applied to the inner faces 15 of the extension bars 14 by slidably engaging the hook portions 41 in the grooves 38 to support the bars 39 against the faces 15 for reducing the unoccupied space between the bars 14 so that opposite sides of a door of a reduced thickness may be engaged snugly between a pair of spacer bars 39. It will be readily apparent that any desired number of pairs of bars 39 may be provided, the individual bars of which will differ from the bars of other sets only in respect to their thickness, to thereby variably adjust the unoccupied space between the extension bars 14.

Assuming that the drill guide 8 is to be employed with a door of a maximum conventional thickness, a portion of which is shown at 42 in Figures 2, 3 and 4, the extension bars 14 are disposed to straddle the door 42 so that their inner faces 15 will abut the opposite sides or the faces of the door 42 and the block 9 is displaced inwardly with respect to the outer, free edge 43 of the door until its end wall 13 and the straight edge 19 abut against the door edge 43. The screw 29 is turned to retract the head 30 and the yoke legs 23 and 24 are then swung upwardly until their terminals are in the same plane as the extension bars 14. The screw 29 is then turned to advance the head 30 inwardly. When the head 30 abuts the outer side of the adjacent bar 14 further turning of the screw 29 in the same direction will cause the portion 21 to slide through the opening 20 until the head 26 abuts the outer side of the other bar 14. The extension bars 14 are sufficiently resilient so that further rotation of the screw 29 to advance the head 30 inwardly will cause the extension bars 14 to be swung inwardly sufficiently to clamp their inner faces 15 against the opposite side of the door 42. It will be readily apparent that the same result will be accomplished when a pair of spacer bars 39 are applied to the bars 14 for fit-

ting the drill guide 8 to a door 42a of reduced thickness, as illustrated in Figure 6. As the door 42 will be snugly engaged between the extension bars 14 either with or without space reducers 39, if desired the yoke 22 may be disposed below the bars 14 as illustrated in dotted lines in Figure 2 and the screw 29 may then be operated in the same manner as previously described for clamping a portion of the door 42 between the heads 10 26 and 30 so that in this manner the drill guide 8 will likewise be rigidly secured to the door 42 with the block end 13 and the bar edge 19 abutting the free edge of the door 43 so that the guide channel or groove 10 will be disposed perpendicular to said edge 43. Accordingly, with the drill guide 8 thus applied to a portion of the door 42 a drill bit 44 may be positioned to rest in the guide channel 10 and will be supported thereby perpendicular to the door edge 43 and centered with respect to the opposite sides or the faces of the door 42. A brace 45 which is disposed beyond the outer end 16 of the block 9 and which is secured by a chuck 46 to the shank end of the bit 44 may then be operated in a conventional manner to advance the bit 44 into the door 42 to form a lock receiving recess 47 which will be centered with respect to the opposite sides or the faces of the door 42 and perpendicular to the door edge 43 provided that the bit 44 is held or allowed to rest in the bed of the guide channel 10 during the drilling operation. In order to make the recess 47 of a desired depth, before the drilling is commenced and with the inner end of the bit abutting the edge 43 the setscrew 36 is loosened and the rod 33 adjusted to position its end 34 against the bit shank and at a distance from the chuck 46 equal to the depth that is desired to drill the recess 47. Accordingly, when the chuck 46 is advanced into engagement 40 with the abutment or stop 34, as illustrated in Figures 2 and 3, the operator will know that a recess of the desired depth is drilled.

The drill guide 8 may be formed of any suitable material preferably a metal having sufficient resiliency to permit the bar extensions 14 to yield toward one another sufficiently to clamp a portion of the door 42 therebetween. The drill guide 8 may be made in various sizes and is obviously capable of other uses in addition to its preferred use previously described.

Various other modifications and changes are likewise contemplated and may obviously be resorted to, without departing from the spirit or scope of the invention as hereinafter defined by the appended claims.

I claim as my invention:

1. A drill guide comprising an elongated block, a pair of spaced parallel furcations extending longitudinally from one end of the block and adapted to straddle and snugly engage opposite sides of a workpiece, a bar secured to one face of and depending from said block and having a straight edge disposed in the same plane as said end of the block, said block end and straight edge being adapted to engage flush against an edge of the workpiece, a yoke-shaped clamp having a straight intermediate portion extending slidably and rotatably through a portion of said bar at right angles to and in a plane parallel to the plane of said furcations and a pair of depending legs, said clamp having a first clamp head at the end of one of said legs, a screw threadedly engaging the end of the other of said legs, a second clamp head supported on said screw, for movement toward and away from the first clamp

head when the screw is revolved, and the surface of said block opposite said one face having a guide channel extending from end-to-end thereof in which a drill bit is adapted to rest for drilling a bore or recess in the workpiece, said guide channel being disposed with its axis at a right angle to the first mentioned end of the block and said edge of the bar and centered with respect to the spaced furcations.

2. A drill guide as in claim 1, and an adjustable stop slidably engaging in said block and having a stop portion disposed beyond the opposite outer end of the block and adjustable toward and away from the adjacent end of said guide channel, means securing the stop in different adjusted positions, said stop portion being adapted to be disposed to be engaged by a brace chuck connected to the bit to adjustably limit the depth of penetration of the bit in the workpiece.

3. A drill guide as in claim 1, an adjustable stop slidably and rotatably engaging in said block and having a stop portion disposed beyond the opposite, outer end of the block and adjustable toward and away from the adjacent end of said guide channel, said stop portion being adapted to be disposed to be engaged by a brace chuck connected to the bit to adjustably limit the depth of penetration of the bit in the workpiece, said stop portion being swingable away from the axis of the guide channel to an inoperative position, and manually actuated clamping means for securing said adjustable stop in a plurality of adjusted positions relatively to the outer end of the block and with said stop portion in either an operative or an inoperative position.

4. A drill guide as in claim 1, the legs of said yoke being substantially parallel and disposed in the same plane, said first clamp head being formed integral with its associated legs and inwardly offset with respect to the axis thereof, said second clamp head being swivelly mounted on the inner end of said screw, said clamping heads be-

ing engageable with the remote sides of the spaced furcations for displacing said spaced furcations into gripping engagement with the opposite sides of the workpiece.

5. A drill guide as in claim 1, and a space reducing member detachably mounted on each of the spaced furcations and bearing against the inner face of the associated furcation for reducing the unoccupied space between the spaced furcations to adapt the drill guide to workpieces of different thicknesses.

6. A drill guide as in claim 1, and a space reducing member detachably mounted on each of the spaced furcations and bearing against the inner face of the associated furcation for reducing the unoccupied space between the spaced furcations to adapt the drill guide to workpieces of different thicknesses, each of said space reducing members including a bar bearing against the inner face of its associated spaced furcation and having hook portions at its top and bottom edges projecting from one side thereof, said spaced furcations having top and bottom edges provided with grooves extending longitudinally thereof and opening outwardly from the free ends of said spaced furcations and slidably receiving said hook portions for detachably mounting the spacing bars against the inner faces of said spaced furcations.
